SOUND FILM AND METHOD OF MAKING SAME

Application filed November 5, 1928. Serial No. 317,289.

This invention relates generally to sound film and more particularly to motion picture film having one or more lines of magnetic sound recording material fixedly and permanently secured thereto. This invention is also concerned with an effective method and means for producing the sound film cheaply and in quantities.

Motion picture film generally in use possesses expansive characteristics peculiar to itself. Changes in temperature or moisture conditions as well as external force exerted on the film, have their corresponding effects on the character and size of the film. For these reasons and for the added reason that the film surfaces are glossy and smooth, it is difficult to effectively and permanently secure any sound record to the film body, and particularly sound records having different expansion coefficients than the film itself. The problem is rendered still more difficult because of the bending and twisting strains and general rough handling which the film undergoes during use, all tending to loosen and separate the sound record from the film. Furthermore, the talking record must be so secured to the film body that its sound recording and reproducing qualities are in no way impaired.

An object of this invention is to provide a sound film having the sound record secured to the film body in a lasting and permanent manner without impairment of the sound qualities of the record.

Another object of this invention is to provide a sound film comprising a magnetic sound record permanently secured to a film body in such a manner as not to render the sound film unduly bulky or unwieldy.

Another object of this invention is the production of a sound film having the magnetic sound record directly associated with the film body, the sound record being of such a character that it will readily expand or contract with the film, and so secured to the film that it will not become unloosened or detached therefrom after long continued hard usage.

Still another object of this invention is to devise a method of securing a sound record

or records to a film body permanently and securely and in a rapid and effective manner.

Still another object of this invention is to devise a method and means for making sound film, which consists generally of means and devices for permanently securing sound record material to a film body securely and effectively and which will enable the manufacturer to produce said film rapidly and at low cost.

Other objects of this invention will be in part obvious and in part pointed out as the disclosure proceeds.

My invention is concerned with the production of sound film and more particularly sound film of the character having a strip or strips of some magnetizable material secured to the body of the film. I have found that granular magnetic material such as iron filings readily retain magnetic impressions corresponding to sound vibrations. The advantage of using granular magnetic material resides in the fact that a strip or pile of granular magnetic material will readily expand and contract with the film body without producing undue strain in and on the film. Difficulty, however, is encountered in securing granular material to the film body in such a manner that the granules will not be rubbed off or their relative position disturbed during the handling or bending of the film.

My sound film consists of a strip or strips of granular magnetic material positioned lengthwise along the film. A coating of glue or cementitious material is first placed upon the film body in which the magnetic granules are embedded. A covering or coating of cementitious material is then placed continuously over the strip or pile of magnetic material in such a manner as to overlap on to the film, and thus, in effect, pocket the magnetic granules between the outside cementitious covering and the film. The cementitious material may be flowed or brushed into position on the film while in a liquid condition, but is preferably of such a nature that it remains hard and solid at ordinary temperatures. The cementitious material may

comprise substantially the same material as the film body.

In order that a clearer understanding of this invention may be had, attention is hereby directed to the accompanying drawings, forming a part of this application and illustrating certain possible embodiments of this invention.

Referring to the drawing, Fig. 1 is an apparatus for making my sound film;

Fig. 2 is a face view of my sound film with certain fragments broken away to illustrate more clearly the structure of the film;

Fig. 3 is an enlarged fragmentary cross sectional view of my apparatus, taken on line 3—3 of Fig. 1;

Fig. 4 is an enlarged fragmentary cross sectional view of my sound film taken on line 4—4 of Fig. 2;

Fig. 5 is an enlarged fragmentary cross sectional view of a sound film of modified construction.

Similar reference characters refer to similar parts throughout the several views of the drawing.

Referring more particularly to Figs. 2 and 4, my sound film generally comprises the usual film body 1 having the photographic emulsion coating or coatings. Incorporated with this film body is the sound record 2 consisting of a strip of magnetizable material, preferably of granular form. Hardened steel filings are excellent for the purpose, although other granular magnetic material may be used within the contemplation of this invention. The magnetizable granules or particles are placed upon the film body in a continuous line and in such a manner as not to interfere with the taking of the picture on the film.

To permanently and immovably secure the magnetic granules or particles to the film body, a strip of cementitious material 3 is first coated onto the film body. The magnetic particles 2 are sprinkled over and embedded in this cementitious strip in a smooth and even layer. I preferably incorporate two sound strips of magnetizable material to each strip of film as shown in Fig. 2, a sound strip being positioned at each side of the film, between the sprocket holes 4 and the picture area. However, only one sound strip may be used, as shown in Fig. 5, and the sound strip or strips may be secured in various positions on the film where they will not interfere with the taking of the picture within the contemplation of my invention.

A layer of cementitious material 5 is now placed over the magnetic particles. This cementitious layer is in the form of a continuous strip of such width as to cover the particles and overlap on to the film body, adhering thereto, and thus pocket the particles between this cementitious layer and the film body. A drying or cooling operation

may then be necessary to harden this cementitious layer. A second cementitious layer 6 may be placed over the first, and of such width as to overlap on to the film body, adhering to the same. The magnetic particles 70 2 are thus in effect embedded or cast into the upper and lower layers of cementitious material and are in addition pocketed within the surrounding cementitious layers and the film body. The relation between the particles 75 cannot thus be disturbed and they are held permanently and securely to the film.

The cementitious material is preferably applied in a fluid or semi fluid condition and should be of such a character as to harden 80 and solidify into a strong and tough material upon cooling or drying. It is necessary that the cementitious layers covering the magnetic particles be hard, to withstand wear, and tough, so that cracks will not form in the 85 same. This cementitious material may be composed of practically the same ingredients as that of the film body, and may be applied to the film body in a semi fluid or molten condition. When solidified these cementitious layers will assume the characteristics 90 of the film body, possessing the same appearance, hardness, toughness, bending and expansion characteristics.

I have discovered that magnetic lines of 95 force, when suitable coils are used and the proper voltage is applied, will travel through film material and cementitious layers generally without hindrance or interruption. The magnetic particles pocketed within the cementitious layers can readily be magnetized 100 to produce the desired sound record by passing the sound strip covered with cementitious layers under the magnetizing pole piece. Reproduction of the sound recorded in the 105 magnetic material is not interfered with by the superimposed cementitious layers.

The magnetic particles should be well compacted together and laid in an even strip for 110 most effective sound recordation and reproduction. It is not necessary that the sound strip have great thickness or breadth, this being largely dependent upon the fineness of the magnetic particles. Since my sound strip secured to the film comprises individual 115 particles compacted together, no external strains are exerted on the film body due to different expansion coefficients of the sound strip and film body. For the same reason there is less tendency for the sound strip to 120 loosen from the film body.

In Fig. 1 I show an apparatus for making 125 my sound film. The film strip 1 is fed from reel 7 and is drawn through the guide rollers 8, 9 and 10 by suitable mechanism such as a sprocket 11. A pressure roller 12 may be provided to keep the film strip in operative engagement with the sprocket. One or more cement pots 13 containing the cementitious substance are suitably supported over 130

the film strip and are each provided with a suitable nozzle or dispenser for coating the strip 3 of the cementitious substance on the advancing film.

5 A corresponding number of receptacles 15 which contain the magnetic particles or iron filings, are provided. Each receptacle is provided with a feed spout 16 which conducts the magnetic particles in an even layer over the glue strip 3. The feed spout may 10 be provided with a suitable valve 17 by means of which the flow of magnetic material to the film may be controlled. Each container may also be equipped with a suitable vibrator or other mechanism for insuring a steady 15 flow of the magnetic particles on to the film strips. For this purpose I suspend the container 15 from a rod 18 or other suitable means. An electric vibrator represented at 20 19 is provided having a vibrating arm 20, pivotally secured to the container. It is seen that by this apparatus the container may be rocked or vibrated rapidly to and fro through a small angle, causing the magnetic particles to flow in a steady and uniform stream to 25 the film.

Another film advancing sprocket 21 and cooperating roller 22 may be provided to aid in advancing the film through the remaining devices of my apparatus. Following the 30 container 15 another set of cement pots 23 are provided. These pots are provided with suitable dispensers 24 for placing the layer 5 of the cementitious material over the strip of magnetic material. This cementitious 35 layer should be of such a width as to completely cover the magnetic strip and overlap each side thereof, adhering to the film body. The dispensers 24 must be of such shape as to lay a uniform layer of the cementitious 40 material of the above width and must be raised above the magnetic strip so as not to disturb the particles. The cementitious material may be forced through the dispenser under regulated pressure if necessary to obtain 45 a uniform layer. A suitable valve 25 may be provided for controlling the flow.

In order that the magnetic particles be 50 concentrated into a uniform strip and held in position prior to covering the same with the cementitious layer, a suitable magnet 26 may be provided, positioned under the film and extending from each feed spout 16 and well beyond the dispenser 24. Magnets 26 aid in obtaining a uniform flow of magnetic 55 particles from the receptacles 15 to the film strip, concentrate the particles into uniform and compact strips and further retain the particles against movement until they have been covered and fixed in position by an overlying cementitious layer.

The film strip may then be run over guide 60 rollers 27 and 28 and partially dried through contact with the air. Drying of the cement cannot be forced as this would cause the film 65 to buckle and curl. The cementitious mate-

rial generally dries quickly and should be dried sufficiently so that it is no longer sticky and yet plastic when it reaches the second set of cooperating pressure rollers 29 and 30. These rollers operate to compact the magnetic 70 particles together and press the plastic overlying cementitious layer firmly to the film. The film strip is then conducted over guide rollers 31 and 32 and under a third series of cement pots 33. These cement pots 75 may be provided with nozzles or dispensers 34 similar to those associated with glue pots 13 and 23.

Nozzles 34 lay a second layer 6 of cementitious material over each of the layers 5 of 80 such a width as to completely cover the same and overlap onto the film body, adhering thereto. The film then passes over guide roller 35 and is generally drawn through this portion of the apparatus by the sprocket 85 wheel 36 and cooperating pressure roller 37. The completed film is then spirally wound up upon a large drying drum 38 where it is exposed to the drying action of the air. The film is placed on the drying drum in a flat 90 condition and the drum is given a slow translatory movement as it rotates causing the film to spirally wind thereon in such a manner that the film strips do not overlap one another. The construction and operation 95 of this drum is described in my copending application Serial No. 698,588 filed March 12, 1924.

To expedite manufacture, reel 7 and drum 38 may be of such size as to carry a wide 100 sheet of film material. The various cement pots, containers, magnets, dryers, etc. may then be duplicated or enlarged so as to lay a number of the sound strips, properly spaced, on the film sheet. The sheet is then 105 properly cut into film strips of proper width and the sprocket holes made therein.

Thus it is seen that I have produced a sound film comprising a film body carrying 110 magnetic sound material which is rugged and adapted to withstand hard service. My sound strips comprising magnetizable particles, pocketed and held to the film body as above described, record and reproduce sounds with the greatest precision and accuracy. The more difficult sounds produced by the speaking voice, such for example as words containing "th" and "S" are faithfully recorded and reproduced. I have also disclosed a method and apparatus for producing 115 my sound film rapidly, and in quantities.

As many changes could be made in the above construction, and as many apparently widely different embodiments of this invention could be made without departing from 120 the scope thereof, it is intended that all matter contained in the above description or shown in the accompanying drawing shall be interpreted as illustrative and not in a limiting sense.

What I claim is:—

A sound film of the character described, including a film body, a plurality of strips of cementitious material coated on said film body, magnetic particles comprising the sound record embedded in said cementitious material, and a plurality of layers of cementitious material extending over said magnetic particles and each overlapping on to the film body to permanently secure the particles to the film and to protect the same against disturbance and injury.

This specification signed and witnessed this 23rd day of October, 1928.

HARRY E. CHIPMAN.
